(57) **CLAIM**

The ornamental design for a building controller as shown and described.

DESCRIPTION

FIG. 1 is a perspective view of a building controller;
FIG. 2 is a front elevational view of the building controller of FIG. 1;

FIG. 3 is a left side view of the building controller of FIG. 1;

FIG. 4 is a right side view of the building controller of FIG. 1;

FIG. 5 is a top side view of the building controller of FIG. 1;

FIG. 6 is a bottom side view of the building controller of FIG. 1;

FIG. 7 is a perspective view of another building controller;
FIG. 8 is a front elevational view of the building controller of FIG. 7;

FIG. 9 is a left side view of the building controller of FIG. 7;

FIG. 10 is a right side view of the building controller of FIG. 7;

FIG. 11 is a top side view of the building controller of FIG. 7; and,

FIG. 12 is a bottom side view of the building controller of FIG. 7.

The portions illustrated in broken lines on the figures form no part of the claimed design.
